US0D1073503S

(12) **United States Design Patent** (10) **Patent No.:** **US D1,073,503 S**
(45) **Date of Patent:** **** May 6, 2025**

(54) **AUTHENTICATION DEVICE INCLUDING FINGERPRINT SENSOR AND DISPLAY**

(71) Applicant: **Bloomberg Finance L.P.**, New York, NY (US)

(72) Inventors: **Philippe Paris Vachon**, Greenwich, CT (US); **Udai Mathur**, Jersey City, NJ (US); **Joel Even**, White Plains, NY (US); **Sean Roarty**, New York, NY (US)

(73) Assignee: **Bloomberg Finance L.P.**, New York, NY (US)

(**) Term: **15 Years**

(21) Appl. No.: **29/760,854**

(22) Filed: **Dec. 4, 2020**

(51) LOC (15) Cl. **10-04**

(52) U.S. Cl.

USPC **D10/104.1; D14/383**

(58) **Field of Classification Search**

USPC D10/65, 75, 78, 104.1; D13/103, 149, D13/162, 184, 1, 99; D18/4.4-4.6, 12.1, D18/56; D3/201, 273; D14/384, 383, D14/356, 300-302, 313, 314, 341, 370, D14/385, 432, 436, 496, 15, 5, 931, D14/240-242, 299

CPC . G07C 9/38; G07C 9/37; G07C 9/257; G06V 40/12; G06V 40/145; G06V 40/10; G06V 40/14

(57) **CLAIM**

The ornamental design for an authentication device including fingerprint sensor and display, as shown and described.

DESCRIPTION

FIG. 1 is a front perspective view of an authentication device including fingerprint sensor and display according to our design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

1 Claim, 4 Drawing Sheets
